(57) **CLAIM**

The ornamental design for the set of mixing bowls, as shown as described.

DESCRIPTION

FIG. 1 is an exploded view of a set of mixing bowls showing my new design;

FIG. 2 is a perspective view of the mixing bowls shown in FIG. 1, showing the bowls nested together;

FIG. 3 is a top, plan view of the nested mixing bowls shown in FIG. 2;

FIG. 4 is a side-elevational view of the nested mixing bowls;

FIG. 5 is a sectional view taken along line 5—5 of FIG. 3.

FIG. 6 is a perspective view of the largest mixing bowl of the mixing bowls shown in FIGS. 1-5;

FIG. 7 is a top, plan view of the mixing bowl shown in FIG. 6;

FIG. 8 is a side, elevational view of the mixing bowl shown in FIG. 6;

FIG. 9 is a perspective view of the second largest mixing bowl of the mixing bowls shown in FIG. 1;

FIG. 10 is a top, plan view of the mixing bowl shown in FIG. 9;

FIG. 11 is a front, elevational view of the mixing bowl shown in FIG. 9;

FIG. 12 is a side, elevational view of the mixing bowl shown in FIG. 9, the opposite side being a mirror image thereof;

FIG. 13 is a perspective view showing one of the four smallest mixing bowls of the mixing bowls shown in FIGS. 1-5, each of the four smallest mixing bowls having the same shape;

FIG. 14 is a front, elevational view of the mixing bowl shown in FIG. 13;

FIG. 15 is a back, elevational view of the mixing bowl shown in FIG. 13;

FIG. 16 is a top, plan view of the mixing bowl shown in FIG. 13;

FIG. 17 is a side, elevational view of the mixing bowl shown in FIG. 13, the opposite side being a mirror image thereof; and,

FIG. 18 is a bottom plan view of the mixing bowl shown in FIG. 13.
